UNITED STATES PATENT OFFICE.

JOHN M. WEISS, OF NEW YORK, N. Y., ASSIGNOR TO THE BARRETT COMPANY, A CORPORATION OF NEW JERSEY.

PLASTIC COMPOSITION.

1,334,061.

Specification of Letters Patent. Patented Mar. 16, 1920.

No Drawing.

Application filed July 3, 1919. Serial No. 308,510.

To all whom it may concern:

Be it known that I, JOHN M. WEISS, a citizen of the United States, residing at 210 West 110th street, New York, in the county 5 of New York and State of New York, have invented certain new and useful Improvements in Plastic Compositions, of which the following is a specification.

This invention relates to the production 10 of new and useful compositions of matter which are sufficiently plastic at elevated temperatures to be molded into different shapes and are capable of retaining such shapes with a considerable degree of tenacity, or may even be made to set and harden 15 so as to resist distortion.

One of the essential ingredients or constituents of the compositions made in accordance with this invention is a bitumen 20 within the standard definition of the American Society for Testing Materials. This bitumen is obtained as a condensable distillate in the final stage of the destructive distillation of coal tar or coal tar pitch and is 25 semi-solid to solid at ordinary temperatures. It has an extremely high boiling point, above 700° F. in many instances but undergoes partial decomposition if distilled at atmospheric pressure. It varies in color from 30 dark brown to a bright cherry red, in melting point from about 110° F. to about 190° F., and in specific gravity from about 1.15 to 1.25, according to the "cut" during the distillation of coal tar or coal tar pitch, and 35 it is relatively free from free carbon. It possesses exceedingly high di-electric strength, is very resistant to dilute acids and alkalies, is unsaponifiable and is soluble in such common solvents as benzol, and coal tar naphtha, etc. This specific bitumen will be referred to in the claims as the "semi-solid to 40 solid bitumen obtainable by the destructive distillation of coal tar pitch."

This bitumen does not lose noticeably by 45 evaporation nor is it readily oxidized when exposed to the air at atmospheric temperatures. After being thinned or dissolved in a solvent either alone or mixed with other ingredients such as gums, resins, linseed oil, 50 etc., it may be applied as a paint or varnish.

When the bitumen is initially produced in an impure state or has an objectionably dark color it may be purified or clarified by careful distillation by steam or vacuum distillation, or may be otherwise treated for the 55

partial or complete removal of the objectionable coloration so as to leave a bitumen which possesses the desired qualities or characteristics and is substantially free from black constituents and free carbon so that 60 the refined or purified bitumen will not materially darken the products or composition for the production of which it is utilized as described below.

According to the present invention this 65 semi-solid to solid bitumen is incorporated with other ingredients to form a composition of matter that is capable of being molded. For this purpose the bitumen described above may be heated until it becomes 70 substantially liquid and there are then introduced into the liquid bitumen comminuted particles or fibers of such material as cork, asbestos, wood, cotton, wool, or paper stock, etc., or a mixture of any or all of them 75 together with pigments, of coloring matter, and loading material such as sand, sizing, etc., if desired. The materials are thoroughly stirred in the liquid after which the batch is permitted to cool somewhat whereupon 80 it becomes plastic so that it is capable of being molded, or extruded through dies of proper shape, or may be passed between rollers to produce sheets.

The bitumen acts as a binder for the 85 comminuted or fibrous particles while these particles serve to strengthen and give rigidity to the composition which would be lacking in the bitumen alone.

Instead of first softening or melting the 90 bitumen and then introducing the other materials, the bitumen may be dissolved in a suitable solvent and the other materials may then be introduced into the solution and thoroughly mixed therewith after which the 95 solvent is removed as by evaporation to leave the composition in suitable condition for being shaped into the desired shapes. Any other practical method may be employed to produce an intimate association of the bitumen and the other constituents of the composition.

The plasticity of the composition, especially at elevated temperatures, is such that the composition can be molded into the desired 105 shapes.

The composition which is produced by this invention can be made to vary in its qualities to a considerable extent by a judicious selection of the other ingredients with 110

which the bitumen is to be compounded and also by selecting different samples of the bitumen which have different melting points or degrees of hardness, and different colors and specific gravities.

10 The composition is useful in many different arts, for example, as fillers for shoes, table tops, boards, etc., or it can be molded into buckets, pails, etc., or used as a coating for wood or concrete, or as a seal for cracks and joints in boxes, buildings, pipes, conduits, etc. Its freedom from attack by acids and alkalis, its pleasing color and its non-volatile and unsaponifiable character render 15 it suitable for a great variety of purposes, unnecessary to enumerate, where such qualities are desirable. After the composition has been shaped into the article it is desired to make, such as pails, for example, the pails 20 may be dipped into the melted bitumen so as to have its surfaces coated with the bitumen, and the articles can be ornamented by stamping or embossing designs upon the surfaces theréof.

25 Claims:

1. As a new product, a composition containing a semi-solid to solid bitumen ob-

tainable by the destructive distillation of coal tar, and other material, said other material being non-liquefiable by heat.

30

2. As a new product, a composition containing a semi-solid to solid bitumen obtainable by the destructive distillation of coal tar, and fibrous material.

3. As a new product, a composition containing a semi-solid to solid bitumen obtainable by the destructive distillation of coal tar, fibrous material, and an artificial coloring matter.

4. As a new product, an article of manufacture, containing a semi-solid to solid bitumen obtainable by the destructive distillation of coal tar and fibrous material, said article being coated with said bitumen.

5. As a new product, an article of manufacture, containing a semi-solid to solid bitumen obtainable by the destructive distillation of coal tar and other material, said other material being non-liquefiable by heat, and said article being coated with said bitu- 50 men.

In testimony whereof I affix my signature.

JOHN M. WEISS.
